US00D841133S

(12) **United States Design Patent** (10) **Patent No.:** **US D841,133 S**
(45) **Date of Patent:** **** Feb. 19, 2019**

(54) **SINK DRAIN HAIR COLLECTOR**

(71) Applicant: **Juka Innovations Corporation**, Farmingdale, NY (US)
(72) Inventor: **Serge Karnege**, Farmingdale, NY (US)
(73) Assignee: **JUKA INNOVATIONS CORPORATION**, Farmingdale, NY (US)

(**) Term: **15 Years**

(21) Appl. No.: **29/662,453**

(22) Filed: **Sep. 5, 2018**

Related U.S. Application Data

(63) Continuation-in-part of application No. 29/641,385, filed on Mar. 21, 2018, and a continuation-in-part of application No. 29/644,282, filed on Apr. 16, 2018, and a continuation-in-part of application No. 14/990,476, filed on Jan. 7, 2016, and a continuation-in-part of application No. 15/464,576, filed on Mar. 21, 2017.
